Henry Whitney

United States Patent Office.

HENRY WHITNEY, OF EAST CAMBRIDGE, MASSACHUSETTS.

Design No. 3,068, dated June 2, 1868.

DESIGN FOR A LAMP-FOOT.

The Schedule referred to in these Letters Patent and making part of the same.

TO ALL PERSONS TO WHOM THESE PRESENTS MAY COME:

Be it known that I, HENRY WHITNEY, of East Cambridge, in the county of Middlesex, and State of Massachusetts, have invented or produced a new ornamental Design for a Foot for a Lamp or other article; and do hereby declare the same to be represented in the accompanying drawings, of which—

Figure 1 is a perspective elevation, and

Figure 2 a bottom view of it.

The base part, A, of the said foot has its corners, *a a a a*, semi-cylindrical, each being flanked by two segments, *b b*, of cylinders, which are connected with those of the next foot by straight faces, *c c*.

The part, B, extending above the base has its lower portion, *d*, formed like the base. The rest extends up from the said portion, and terminates at top in a hexagon, *e*, surmounted by a hexagonal frustum, *f*, which is capped by an ovolo or bead, *g*, and by a notched tenon, *h*, extended above the said bead, the whole being as represented.

I claim, as my invention or production—

The said design for a lamp-foot, substantially as shown and described.

HENRY WHITNEY.
